UNITED STATES PATENT OFFICE.

WALTER W. ERLEWINE, OF LONG BEACH, CALIFORNIA, ASSIGNOR TO MARION MACHINE, FOUNDRY & SUPPLY COMPANY, OF MARION, INDIANA, A CORPORATION.

WINDLASS CONSTRUCTION.

Application filed February 7, 1927. Serial No. 166,421.

The object of this invention is to speed the work of a windlass construction in hoisting or pulling operations. In the trade this invention is called a "speed spool for calf or 5 bull wheels," but the invention is not limited to any particular form of windlass construction or any particular use.

The invention has been used chiefly in connection with a bull or calf wheel in oil well 10 operation, for raising or pulling tubing, casing and sucker rods in oil wells and the like.

In the ordinary windlass construction, such as a bull or calf wheel, there is one 15 diameter of winding shaft or drum so that the winding speed is dependent on the diameter of such shaft or drum. Usually the winding shaft of a bull or calf wheel is 13 inches in diameter, although sometimes it is 16 inches. The hoisting or pulling operation by the ordinary bull or calf wheel is relatively slow, due to the relative small diameter thereof. This small diameter is necessary because in doing some of the work, such as the initial pull on a casing or tubing 20 or sucker rod a powerful and slow movement is desired.

The chief feature of this invention consists in removably securing on a portion of the power driven winding shaft of the windlass construction one or more winding spools or constructions of greater diameter than the shaft with tapering end flanges arranged so that the cable can readily be wound from the shaft onto the spool or drum or unwound 35 therefrom onto the shaft in the rapid operation of the machine.

Ordinarily this added spool or drum of greater diameter than the shaft is called in the trade a "speed spool" and where the 40 diameter of the shaft is 13 inches the speed spool is about 20 inches, so that the hoisting or pulling speed on the windlass construction can be increased or the operation thereof may, at the beginning, be slow and afterwards the speed is increased, according to 45 the demands of the work being done.

The full nature of the invention will be understood from the accompanying drawings and the following description and 50 claims.

In the drawings, Figure 1 is a view of a portion of the windlass construction, partly in plan view, and partly in central longitudi-

dinal section, parts being broken away. Fig. 2 is a view of the right hand end of Fig. 1, 55 part being in plan view and a part in central longitudinal section on the line 2—2 of Fig. 1. Fig. 3 is a view, partly in end elevation and partly in cross section on the line 3—3 of Fig. 1. Fig. 4 is a view of a modified 60 form, partly in plan view and partly in central longitudinal section and parts being broken away. Fig. 5 is a view of the right hand portion of Fig. 4, being partly in plan view and partly in central longitudinal section 65 and parts being broken away. Fig. 6 is a section on line 6—6 of Fig. 4, showing the flanges in end elevation.

In Fig. 1 there is shown a power shaft 10 of a windlass construction of the type commonly called a bull wheel or calf wheel, which is driven by suitable power means not herein shown, and on which a cable 11 winds and unwinds in the work of the machine. Ordinarily this shaft is about 13 70 inches in diameter and, therefore, operates relatively slowly and is preferably utilized in this construction while doing heavy work when slower operation and greater pulling power are desired.

On a portion of the winding shaft 10 a speed spool or drum 12 is removably secured, as seen in Fig. 3. This spool or drum is of greater diameter than the shaft 10, say 20 inches in diameter, so that its winding action is more speedy than that of the shaft 10. It is secured at each end to an end flange 13 that is clamped or otherwise secured on the shaft 10. This flange is of greater diameter than the spool or drum 12, as seen in 90 Fig. 2, to prevent the escape of the cable from the spool or drum, and it tapers down to the shaft 10 and has a recessed portion 14 for the ready passage of the cable from the shaft 10 to the spool, as shown in Fig. 1. 95 This recess or groove 14 starts at the shaft 10 and passes up to the spool or drum 12, and for that reason the marginal portion of the end flange 13 is notched or cut down so as to register with the external surface 100 of the spool or drum 12.

The foregoing construction enables the machine to operate and work first with the shaft 10 of relatively small diameter for starting the work, such as pulling a casing, 105 tubing or sucker rod in an oil well, and after

it has started and the pull becomes less, and greater speed more desirable, the cable is run up across the end flange 13 from the shaft 10 to the spool or drum 12, and then the cable is operated at a greater speed than before. This gives to the windlass construction a plurality of speeds for one cable.

Since the pull on the cable on the spool 12 may be very great, spacers 114 are provided 10 within the drum and between it and the shaft 10. Each spacer, therefore, is a ring slideable on the shaft 10 and within the spool or drum 12. The spacer is formed of two semi-circular halves with their abutting ends provided with laterally extending ears 15 through which bolts 16 extend for securing them together. Any number of these spacers may be used according to the length of the spool or drum 12. Usually there are at least 20 three of them, but there may be more supporting each spool or drum 12.

In mounting the speed spool on the shaft 10, the spacers 114 are first placed on the shaft and then the drum 12 is slipped over the 25 spacers. These drums are unitary, that is made of one piece preferably, and at one end of the spool or tube 12 is preferably turned down as shown at 17 in Fig. 3 and enters a corresponding circular recess or seat in the 30 flange member 13. The flange member also has a hub portion 18 which the spool 12 surrounds and is secured to by screws 19. This arrangement is for the purpose of effecting a very secure and rigid connection between 35 the flange 13 and spool 12 so as to hold the spool in place, and particularly to prevent separation of the flange from the spool by the enormous strain on it caused by the cable doing heavy work. The flange member 13 is 40 made of semicircular halves, as shown in Fig. 3, with a tapering body portion, as indicated in Fig. 2, extending out as far as the diameter of the spool 12, and then the flange extends considerably beyond the spool 12 so as to prevent 45 the cable from slipping off the spool.

The flange is provided with ribs 20, as shown, for reinforcing it, and the two halves are secured together by bolts 21 extending through adjacent ribs 20. The end flange is 50 partially cut up at 14 to form a recess or groove for the passage of the cable from the shaft 10 to the drum 12 as seen in Fig. 1. This groove or passage 14 for the cable from the shaft 10 to the drum 12 is seen in Fig. 1. 55 This groove or passage for the cable over the flange is preferably inclined both to lines transversely of the axis of the shaft 10 and parallel therewith as indicated in the drawings. The transverse inclination is in the direction opposite to the direction of travel of the flange 13 or shaft 10 so as to furnish an easy means of carrying the cable from the shaft to the speed spool.

Ordinarily this invention has only one 60 speed spool 12 but, if desired, a plurality of

speed spools may be employed in series form, as shown in Fig. 4, where there is a second speed spool 112 mounted on and around the speed spool 12 in the same manner that the speed spool 12 is mounted on the shaft 10. 70

The outer spool 112 is shorter in length than the spool 12 on which it is mounted so that the cable can be partly wound on the shaft 10 and thereafter carried to the spool 12 of a greater diameter and then be carried 75 to the spool 112 for even a greater speed.

The outer spool 112 requires a flange 113 similar to the end flange 13, excepting it is of greater diameter. When two concentric speed spools or drums are employed, as shown 80 in Fig. 4, the left hand end of said spools may be mounted on a single end flange 213. This is like the other flange excepting it is mounted on the shaft 10 and has two hubs 18 and 118, the former extending further inward than the latter for mounting the ends of the two spools or drums. However the details of form of the different flanges may be modified as desired by the builder and preferably the spacer 214 and flange 113 for the 85 outer drum should surround the spacers 114 for the inner drum to give a stronger support for the outer spool in resisting the pull of the cable.

While details and dimensions are herein 90 given, the invention is not limited to them as they may be obviously varied to suit the desires of the manufacturer or purchaser and according to the work to be done.

I claim as my invention:

1. A change speed windlass construction including a cable winding member of relatively small diameter, a cable winding tubular member of greater diameter removably mounted on a portion of said smaller member, an annular flange surrounding the smaller member and connected with each end of the larger member and having an inclined groove therein for the cable to pass from one member to the other, and a spacer removably mounted on the smaller member for supporting the larger member intermediate its ends substantially as set forth.

2. A change speed windlass construction including a cable winding member of relatively small diameter, a cable winding tubular member of greater diameter removably mounted on a portion of said smaller member, an annular flange surrounding the smaller member and connected with each end of the larger member and provided with an integral annular shoulder extending into and secured to each end of said member for supporting the same and having an inclined groove therein for the cable to pass from one member to the other.

3. A change speed windlass construction including a power driven shaft, a cable therefor, a small speed spool removably secured on a portion of the said shaft and being of

greater diameter than the shaft and spaced therefrom, a larger speed spool removably secured on a portion of said small speed spool and being shorter than the small speed spool 5 and spaced therefrom, and flanges for mounting said spools concentrically of the shaft and of each other and having inclined grooves for the cable to pass from the shaft to the spools and from the small spool to the larger 10 spools substantially as set forth.

4. A windlass construction including a power driven shaft, a cable therefor, a small speed spool removably secured on a portion of said shaft and being of greater diameter than 15 the shaft and spaced away from the shaft, a tapering flange secured to the end of the spool and of greater diameter than the spool and sloping downward to the shaft and having a recess therein through which the cable may be 20 led from the shaft to the spool, a larger speed spool removably secured on a portion of said small speed spool and being spaced therefrom, a flange secured to the end of said large speed

spool and mounted on said small speed spool 25 and sloping downward thereto and having a recess therein for the cable to be led from the small spool to the large spool, and annular spacers within and supporting said spools between their ends, substantially as set forth.

5. A windlass construction substantially as 30 set forth in claim 4, with the flange secured to the end of the larger spool surrounding the smaller spool, and the spacer in the smaller spool.

6. A windlass construction substantially as 35 set forth in claim 4 with a single flange for supporting both of said spools at one end of the construction, said flange being mounted on said shaft and having two annular hubs of different diameters and one offset with relation to the other, and means for securing the spools respectively to said hubs, substantially 40 as set forth.

In witness whereof, I have hereunto affixed my signature.

WALTER W. ERLEWINE.
